UNITED STATES PATENT OFFICE

152,633

DESIGN FOR A KNIFE

Syrie Maugham, New York, N. Y.

Application December 13, 1947, Serial No. 143,126

Term of patent 3½ years

(Cl. D22—3)

To all whom it may concern:

Be it known that I, Syrie Maugham, a subject of the Kingdom of Great Britain, residing at 157 West 57th Street, New York, New York, have invented a new, original, and ornamental Design for a Knife, of which the following is a specification, reference being had to the accompanying drawing, forming part thereof.

Fig. 1 is a side view of the knife, showing my new design;

Fig. 2 is an edge view thereof; and

Fig. 3 is a sectional view along the line 3—3 of Fig. 1.

I claim:

The ornamental design for a knife, as shown.
SYRIE MAUGHAM.
